(57) **CLAIM**

The ornamental design for a sight mount, as shown and described.

DESCRIPTION

FIG. 1 is a top front perspective view of a sight mount, showing my new design in an environment of use;

FIG. 2 is a top front perspective view of the sight mount of FIG. 1;

FIG. 3 is a bottom rear perspective view of the sight mount of FIG. 1;

FIG. 4 is a right-side plan view of the sight mount of FIG. 1;

FIG. 5 is a left-side plan view of the sight mount of FIG. 1;

FIG. 6 is a front plan view of the sight mount of FIG. 1;

FIG. 7 is a rear plan view of the sight mount of FIG. 1;

FIG. 8 is a top plan view of the sight mount of FIG. 1; and, FIG. 9 is a bottom plan view of the sight mount of FIG. 1. The broken lines in FIG. 1 drawing depict unclaimed environment only and form no part of the claimed design.

1 Claim, 7 Drawing Sheets
